Mr. & Mrs. H. K. Parsons
ATTORNEYS

UNITED STATES PATENT OFFICE.

GEORGE H. DAY, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

EYE-PROTECTOR.

1,278,444.

Specification of Letters Patent. Patented Sept. 10, 1918.

Application filed March 12, 1917. Serial No. 154,323.

To all whom it may concern:

Be it known that I, GEORGE H. DAY, a citizen of the United States, residing at Southbridge, in the county of Worcester and 5 State of Massachusetts, have invented certain new and useful Improvements in Eye-Protectors, of which the following is a specification.

This invention relates to improvements in 10 eye protectors and has particular reference to structures especially adapted for use in the industries.

One of the leading objects of the present invention is the provision of a simple, efficient and durable construction of eye protector which may be readily adjusted to fit the face of the wearer.

Another object of the invention is the provision of a construction in which the several parts are securely and firmly united and have sufficient rigidity to maintain their desired adjusted relation, but which are so constructed as to be capable of adjustment without the use of pliers or other tools to obtain a satisfactory fit of the protector on the face.

Other objects and advantages of my improved construction should be readily apparent by reference to the following specification taken in connection with the accompanying drawings, and it will be understood that I may make any modifications in the specific details of construction shown and described within the scope of the appended 35 claims without departing from or exceeding the spirit of my invention.

Figure I represents a front elevation of one form of my improved protector.

Fig. II represents a similar view illustrating an adjustment of the parts shown in Fig. I.

Fig. III represents a sectional view taken as on the line III—III of Fig. I.

Fig. IV represents a similar view of a 45 slightly modified construction.

Fig. V represents a front view of a slightly different form of my invention.

Fig. VI represents a similar view illustrating an adjustment of this form of construction.

Fig. VII represents a sectional view as on the line VII—VII of Fig. V.

Fig. VIII represents a similar sectional view of a slightly modified construction.

Fig. IX represents a view similar to Fig. VIII illustrating an adjustment of the parts.

Fig. X represents a plan view of the construction illustrated in Fig. I.

Fig. XI represents a plan view of the construction illustrated in Fig. VI.

In the drawings, in which similar characters of reference are employed to denote corresponding parts throughout the several views, the numeral 1 designates the rims for the lenses 2, which rims are preferably provided with temples or retaining devices 3 for securing the mounting in position on the face.

In the form of the invention illustrated in Figs. I to IV inclusive, I have shown the 70 bridging or lens connecting members as formed from a single strip of material, starting as at the point 4, where one end is attached to the lenses extending across between the lens rims in the looped transversely 75 and downwardly or diagonally extending portion 5 attached as at 6, at a diagonally opposite point from the first lens frame to the second lens frame, then being formed into the loop or spiral 7 terminating in a 80 transverse portion 8 and suitably secured to the crest pad 9, beyond the crest pad, having a second loop 10 corresponding to the loop 7 at the other side and terminating in a second diagonally extending connecting 85 member 11, corresponding in all essential respects to the original transverse member 5.

It will thus be noted, particularly by reference to Fig. II, that the frame just described has great possibilities for adjustment for pupillary distance, by separation of the frame through opening out of the loops 7 and 10 and through partial straightening of the looped cross members 5 and 11, while at the same time the vertical height 95 90 and in and out adjustment of the crest pad 9 are readily varied as desired by opening or closing, by winding movement of the loops 7 and 10, or by desired distortion of the loops.

This adjustment may in part be readily understood by a comparison of Figs. III and IV, where different adjustments of the crest pad are illustrated, attention in connection with these figures, however, being 105 invited to the fact that in Fig. III the loop is shown as extending rearwardly and downwardly to the crest pad, while in Fig. IV the loop is shown as extending forwardly and then downwardly, these two being alternative construction, either of which may be employed as desired, and both of which will 110

present substantially the same frontal appearance and embody the same general structural features.

It will be noted that the construction just described is a one piece construction. If desired to form the bridge or lens frame connecting members in two separate parts I may if preferred make use of a construction such as for example that shown in Figs. V to IX inclusive, in which I have shown the upper looped and adjustable bridging or connecting member 12, and the bridge or nose engaging member 13 having integral therewith, if desired, or separate therefrom and secured thereto, as in the preceding forms, the lateral extending or looped members 7 and 10, which, as in the forms just described, may extend either to the rear and then forwardly to the nose engaging member, or forwardly and then rearwardly to the nose engaging member, alternative constructions being shown in Figs. VII and VIII respectively. In either event, however, the bridging member may be adjusted as desired, either by direct upward and downward or in and out pulling movement, or preferably by a slight winding movement tending to open up or tighten the coils of the loops 7 and 10 to most neatly and at the same time satisfactorily relatively adjust the parts. The possibilities of adjustment are in part illustrated and should be understood by a comparison of Figs. VIII and IX, showing two adjustments of the same general form of construction.

I claim:

1. An eye protector including lens frames, a connecting member formed from a single strip of material having each end attached to the lens frames, thence extending inwardly across between the frames, looped transversely and downwardly and attached to the opposite lens frame, then formed into a spiral terminating in a transverse portion, and a crest pad secured to the transverse portion.

2. An eye protector including lens frames, a connecting member formed from a single strip of material having each end attached to the lens frames, thence extending inwardly across between the frames, looped transversely and downwardly and attached to the opposite lens frames, then formed into a spiral loop, the intermediate portion of said strip terminating in a transverse portion and having connected thereto a central crest rest and a crest pad secured thereto for vertical in and out and angular adjustment relative to the lens frames.

60 3. In an eye protector, the combination

with lens retaining means, of lens connecting means, including a flexible upper connecting member adapted to be bent or flexed in adjustment of the distance between the lenses, and a lower member in connection with the upper member comprising a nose rest and extension loops connected with the rest at the sides thereof and adapted to be opened or compressed in varying the distance between the lenses and to be opened or tightened in the plane of the loops to permit of the variance of the vertical and in and out adjustment of the nose rest.

4. In an eye protector, the combination with the lenses, of a round wire scroll member having one end secured to each of the lenses and formed in a wide scroll lying substantially in the plane of the attached ends thereof, the opposite ends of the scroll being inwardly deflected and having connected thereto a central crest rest whereby the crest rest is supported for vertical, in and out, and angular adjustment relative to the lens frame, while the distance between the lenses may be varied by distortion of the plane of the scroll.

5. The combination with a pair of lens frames, of an adjustable member connecting the lenses and normally holding them in fixed relation one to the other, a nose rest, and a looped member extending from each end of the nose rest to the adjacent frame for adjustably connecting the parts.

6. A one piece center for an eye protector or the like, comprising a pair of oppositely disposed diagonally extending looped connecting members terminating at each end in a helix or coil, of a curved central portion integral with and connecting the inner ends of the helices.

7. The combination with a pair of lens frames, of means for rigidly holding the frames in desired adjusted position, a nose rest disposed below the lens frame, positioning means, an adjustable support for the nose rest comprising ram's horn loops connected at one end to the nose rest and at the opposite end to the lens frame to permit of universal adjustment of the nose rest with respect to the lens frames and to accommodate desired adjustment of the lens frames with respect to each other and the centrally disposed nose rest.

In testimony whereof I affix my signature in the presence of two witnesses.

GEORGE H. DAY.
